CLAIM

The ornamental design for a container for holding liquid for refilling an e-cigarette device, as shown and described.

DESCRIPTION

FIG. 1 is a perspective view of the container for holding liquid for refilling an e-cigarette device.

FIG. 2 is a back view of the container for holding liquid for refilling an e-cigarette device.

FIG. 3 is a front view of the container for holding liquid for refilling an e-cigarette device.

FIG. 4 is a left side view of the container for holding liquid for refilling an e-cigarette device.

FIG. 5 is a right side of the container for holding liquid for refilling an e-cigarette device.

FIG. 6 is a top plan of the container for holding liquid for refilling an e-cigarette device; and,

FIG. 7 is a bottom plan of the container for holding liquid for refilling an e-cigarette device.

The broken lines in the figures depict portions of the container for holding liquid for refilling an e-cigarette device that form no part of the claim.
